UNITED STATES PATENT OFFICE.

ROBERT K. SCHUTT, OF CHICAGO, ILLINOIS.

FLAT-ARCH CONCRETE FLOOR CONSTRUCTION.

Application filed March 1, 1926. Serial No. 91,311.

This invention relates more particularly to a floor construction having a plurality of flat arches formed of a key tile and haunch blocks which are so set to permit reinforced concrete joists to separate the flat arches for producing a floor construction capable of sustaining its own weight in addition to a superimposed load.

It is an object of this invention to provide a concrete floor construction wherein a series of hollow tiles are arranged to form flat arches separated by reinforced ribs or joists adapted to receive the loads and carry the same to the main beams or supporting walls of a building.

It is also an object of this invention to provide a flat arch concrete floor construction covering a combination of flat arches and reinforced concrete adapted to carry maximum loads with a minimum thickness of floor slab and of dead weight.

Another object of the invention is to provide a concrete floor construction adapted to use a minimum quantity of the more weighty and expensive materials such as steel and concrete with a maximum use of the cheaper and lighter materials such as hollow tile or blocks.

It is furthermore an object of this invention to provide a concrete floor construction adapted to employ reinforced concrete joists running in one or in two directions for the purpose of carrying loads in either one or both directions, to the supporting beams or girders to meet individual requirements, such as a floor construction embodying hollow tile flat arches separated reinforced concrete joists with the upper and lower areas of the flat arches exposed or having the entire area of the supporting arches covered with a coating of concrete to afford an added structural value in resisting stresses as well as providing a hard smooth surface for the floor.

It is an important object of this invention to provide an improved concrete floor construction of simplified, inexpensive construction and of reduced weight combining the use of flat tile arches having concrete or tile keys with reinforced concrete supporting joists to produce a practical and economical system of floor construction.

Other and further important objects of this invention will be apparent from the disclosures in the specification and the accompanying drawings.

The invention, in a preferred form, is il-

lustrated in the drawings and hereinafter more fully described.

On the drawings:

Figure 1 is a fragmentary plan view of a section of a flat arch concrete floor construction embodying the principles of this invention and having reinforcements lengthwise and crosswise of the floor construction.

Figure 2 is a fragmentary vertical section taken on line II—II of Figure 1.

Figure 3 is an enlarged fragmentary vertical section taken on line III—III of Figure 1.

Figure 4 is a fragmentary top plan view of a modified form of floor construction wherein the reinforcement runs in one direction only.

Figure 5 is an enlarged transverse vertical detail section taken on line V—V of Figure 4.

Figure 6 is a vertical detail section taken on line VI—VI of Figure 4.

Figure 7 is a fragmentary transverse vertical section of another modified form of floor construction using different types of hollow tiles to permit the use of reinforced T-cross sectioned joists.

Figure 8 is a fragmentary vertical section through another modified form of floor construction using a different style of hollow tile and having the flat arches completely covered with concrete.

Figure 9 is another vertical detail section through still another modified form of concrete floor construction wherein the hollow tile is positioned to permit the formation of concrete keys therebetween with the upper areas of the flat arches completely covered with concrete.

Figure 10 is a fragmentary vertical section through a modified form of floor construction wherein hollow tile of the type illustrated in Figures 8 and 9 is used with the upper and lower areas of said tile exposed.

Figure 11 illustrates a vertical detail section through another modified form of floor construction using another type of hollow tile permitting the formation of concrete keys and reinforced concrete T-cross sectioned joists between the flat tile arches.

Figure 12 is an end view of one type of hollow tile having the end thereof covered by a metal or fiber cover.

Figure 13 is a side elevation of the tile and cover illustrated in Figure 12.

As shown on the drawings:

Referring to Figures 1, 2 and 3, the reference numeral 1 indicates a plurality of vertical concrete columns connected by reinforced concrete beams 2. The improved flat arch concrete floor construction consists of a plurality of parallel flat arches each comprising a plurality of haunch blocks 4 separated by hollow key tile 4' having inclined side faces. The key tile 4' is inverted as clearly illustrated in Figure 3 and is positioned between the haunch block 4 to form a key or wedge block. The flat arches are arranged adjacent one another to form a filler or form with each filler having the ends thereof reduced in width as it nears the supporting beams. This reducing of the width of the ends of the fillers is produced by reducing the number of hollow tiles in the end arches from three to two and then to one piece, thereby affording an arrangement which makes it possible to leave sufficient concrete in depth and breadth near the supporting beam to take care of shearing and negative compression stresses. As clearly illustrated in Figure 1 the parallel flat tile arch fillers are formed of a plurality of arches, certain groups of which are separated from one another. The flat arches as just described are placed upon a temporary floor form in proper spaced relation after which concrete is poured around said flat arches and over reinforcing rods 5 thereby forming reinforced wedge-shaped longitudinal concrete joists 6 and reinforced transverse concrete joists 7. The reinforced concrete joists 6 separate the parallel fillers while the reinforced concrete joists 7 separate the group of flat arches comprising the fillers. It will thus be seen that Figures 1, 2 and 3 illustrate an improved flat arch concrete floor construction of a type wherein the floor is reinforced both lengthwise and crosswise at right angles to each other thereby distributing the load of the floor panel to the supporting beams or four sides of the floor panel. A two-way system of reinforced floor construction is thus provided permitting the carrying of maximum loads on a given span with a minimum use of material, a reduced thickness of floor construction as well as a reduction of the dead weight of the floor.

Figures 4, 5 and 6 illustrate a modified form of flat arch concrete floor construction wherein the reinforcement runs in one direction only. In this type of construction a plurality of parallel flat arch fillers are employed, each made up of a plurality of hollow haunch blocks 8 having their upper longitudinal outer corners notched as at 9. The haunch blocks 8 are separated by a key or wedge tile 10, as clearly illustrated in Figure 5. The flat arch fillers have the end portions thereof reduced in width similar to the arrangement hereinbefore described in connection with Figure 1. The flat arch fillers are mounted on a temporary floor form in

parallel relation as illustrated in Figure 4 after which concrete is poured between the fillers over reinforcing rods 11 to form T-cross sectioned connecting joists 12. The T-cross-sectional construction of the reinforced joists 12 is made possible by the use of the haunch blocks 8 having the notched portions 9 therein so positioned that a T-cross sectioned area is provided between adjacent flat arches. 75

Figure 7 illustrates a modified form of floor construction wherein hollow intermediate tiles 13 and haunch blocks 14 are arranged in groups with the hollow tiles 13 inclined in opposite directions with the outer faces thereof of abutting against inclined faces of the haunch blocks 14. The haunch blocks 14 are of less height than the tiles 13 thereby affording an off-set. The tiles 13 and 14 are arranged to form a flat arch having a wedge-shaped groove disposed longitudinally thereof of which when filled with concrete affords a concrete key 15. Reinforcing members or tie rods 16 are positioned in groups between adjacent flat arches and are covered with concrete to form T-cross sectioned joists 17 acting to hold the hollow tiles 13 and 14 of each flat arch in arched relation to form a completed reinforced floor construction. 80

Figure 8 illustrates another modified form of concrete floor construction wherein a plurality of hollow wedge shaped tiles 18 are arranged in groups, with the intermediate or key tile in inverted position between the two outside tiles or haunch blocks to form a flat arch, the tile members of which are adapted to be held in arched relation by pouring concrete between the flat arches over reinforcing rods 19 to form reinforced concrete joists 20. The concrete is poured to flow over the top of the flat arches to form a thin layer of concrete 21 to produce a reinforced concrete floor structure having a hard upper face. 90

Figure 9 is a modified form of concrete floor construction similar to that illustrated in Figure 8, with the exception that the hollow tiles 18 are arranged with the intermediate tile 18 positioned the same as the haunch blocks thereby affording longitudinally disposed concrete keys 22 between adjacent arches of the floor structure. 105

Figure 10 illustrates another modified form of concrete floor construction wherein hollow key-shaped tiles 23 are positioned to form a longitudinal groove therebetween, adapted to be filled with concrete to form a concrete key 24. The space between adjacent flat arches is provided with reinforcing rods 25 covered by concrete which forms a joist 26. The reinforced joists 26 acts to hold the tiles of each of the flat arches tightly compressed against the sides of the respective concrete keys 24 to form the completed reinforced floor structure. 120

Figure 11 illustrates still another form of 125

reinforced concrete floor wherein hollow tiles 27 are positioned with the inclined surfaces thereof diverging upwardly to afford a longitudinal groove which is filled with concrete 5 to form a concrete key 28. Each of the hollow tiles 27 is notched as at 29 along the upper outer longitudinal edge. Each of the flat arches comprises two hollow tiles 27 thereby affording a T-cross sectioned area 10 between adjacent flat arches which is filled with concrete to cover reinforcing rods 30 to form reinforced T-joists 31.

Figures 12 and 13 illustrate a hollow wedge tile 32 provided with a metal or fiber closure plate 33 to close one end of the tile to prevent concrete from running into the tile. It will, of course, be understood that the end tile members of the various fillers hereinbefore described may be provided with closure 15 plates 33 so that there will be no waste of concrete resulting from concrete flowing into the open ends of the end tiles forming the various fillers. The use of the closure plates 33 not only prevents a waste of material but 20 also prevents any increase in the dead load to be carried by the floor structure.

In the formation of the reinforced flat arch floor structures hereinbefore described, it, of course, will be understood that the tile arches 30 are placed on temporary forms of false work which securely support the entire structure in place until the concrete has been poured and allowed to set sufficiently over the reinforcing rods and between the flat arches. It 35 will thus be seen that the improved flat arch concrete floor construction is adapted to meet all the requirements as to the various stresses and strains and employs only a minimum of the expensive materials such as steel and concrete with a maximum use of the cheaper and lighter materials such as the hollow tiles or blocks. A marked reduction in the cost of materials as well as a simplified practical method of installation or erection is obtainable with the improved flat arch construction 40 of this invention.

I am aware that numerous details of construction may be varied through a wide range without departing from the principles of this 50 invention, and I therefore do not purpose limiting the patent granted hereon, otherwise than necessitated by the prior art.

I claim as my invention:

1. A concrete floor construction comprising a plurality of reinforced concrete joists 55 separating a plurality of flat fillers tapered

at the ends and each constructed of hollow tiles separated by concrete keys and held in associated position by said reinforced concrete joists.

2. The combination with a reinforced concrete floor slab, of a plurality of flat arches forming a part of said slab and positioned in parallel spaced relation to form a filler with tapered ends, each of said flat arches comprising a plurality of hollow blocks separated by concrete wedge members extending from the top to the bottom of said filler.

3. A concrete floor construction comprising a plurality of parallel flat arches constructed of hollow tiles arranged in abutting relation and associated to form fillers reduced in width at the ends, concrete poured between the tiles of each arch to form concrete keys, reinforcing members positioned 70 between the fillers and concrete poured over said reinforcing members and between said fillers to form reinforced joists having enlarged ends filling the space between the reduced ends of the fillers to form the floor.

4. A concrete floor construction comprising a plurality of reinforced beams, a plurality of flat arches positioned between said beams to form fillers having tapered ends, with each flat arch comprising a plurality of 85 hollow tile having inclined faces, said tile being grouped in keyed relation with one another by concrete wedge keys formed between the tile, reinforcing rods between said fillers and concrete filling the space between 90 said reinforced beams and said flat arches to form reinforced joists having enlarged end portions adapted to unite with said flat arches to form the completed reinforced floor.

5. A concrete floor construction comprising groups of hollow tile members having inclined faces and arranged in groups to form flat arches, with said arches having the tile members disposed in staggered rows to 100 form fillers having tapered ends, reinforcing members positioned between said arches and concrete poured between said arches and tile members to form concrete keys between said tile members and reinforced concrete joists 105 between said arches which serve to hold the flat arches in an arched position to form the completed floor.

In testimony whereof I have hereunto subscribed my name.

R. K. SCHUTT.
